INVENTOR

BY *Victor J. Evans*

ATTORNEY

UNITED STATES PATENT OFFICE

RALPH W. THIBODEAU, OF QUINCY, MASSACHUSETTS

GLARE DEFLECTOR

Application filed October 16, 1929. Serial No. 400,052.

This invention relates to a glare deflector for headlamps of automobiles and the like, the general object of the invention being to provide a member adapted to be placed in the lower part of the reflector of the lamp and having upstanding deflector members thereon which deflect the rays of light which ordinarily strike the bottom of the reflector to the top of the reflector so that such rays are prevented from passing upwardly and forwardly and thus blinding the drivers of approaching vehicles and pedestrians.

This invention also consists in certain other features of construction and in the combination and arrangement of the several parts, to be hereinafter fully described, illustrated in the accompanying drawings and specifically pointed out in the appended claim.

In describing the invention in detail, reference will be had to the accompanying drawings wherein like characters denote like or corresponding parts throughout the several views, and in which:

Figure 1 is a sectional view through a lamp provided with my device.

Figure 2 is a front view of Figure 1.

Figure 3 is a perspective view of the device without the ribs or flanges.

Figure 4 is a view of one of the flanges.

In these views, the numeral 1 indicates the body of the device which tapers from its front end to its rear end and is of arc shape in cross section, so that when placed in the reflector 2 of a lamp A, the body will cover the lower portion of the reflector. The body is formed with the depending projections 3 which are adapted to be passed through holes formed in the lower part of the reflector and then bent so as to attach the device to the said lower part of the reflector, as shown in Figures 1 and 2. The rear end of the body may be formed with a substantially semi-circular part 4 to fit around a part of the lamp socket and the bulb and the body is also provided with a plurality of slots 5 arranged in transverse rows to receive the tongues 6 of the strips 7 which are also of arc shape, as shown in the drawings.

These strips are so arranged that they will reflect the rays of light upwardly, which

ordinarily strike the bottom of the reflector so that these rays will be reflected downwardly by the upper part of the reflector, as shown in Figure 1. Thus the device prevents any of the rays of light being directed upwardly and forwardly so that with this device, glare and blinding of the drivers of approaching vehicles is prevented.

It is thought from the foregoing description that the advantages and novel features of the invention will be readily apparent.

It is to be understood that changes may be made in the construction and in the combination and arrangement of the several parts, provided that such changes fall within the scope of the appended claim.

What I claim is:

A glare deflector comprising a body tapering gradually from one end to the opposite end thereof and transversely and longitudinally curved to conform to the contour of the lower portion of a reflector, projections formed on the edges of the body and extending angularly thereof to engage the reflector for supporting the body in a slight space relative thereto, an arcuate shaped member formed on the smallest end of the body to engage under the illuminating means of the reflector, said body having relatively spaced rows of slots arranged transversely of said body, arcuately curved reflecting elements arranged transversely of the body and in alignment with the rows of slots, and tongues on the reflecting elements and extending through the slots and bent against one face of said body and spaced from the reflector by the projections.

In testimony whereof I affix my signature.

RALPH W. THIBODEAU.
